UNITED STATES PATENT OFFICE.

FRANK J. BECKER, OF HAMILTON, OHIO.

MOLDING-FLASK.

1,096,668.

Specification of Letters Patent. Patented May 12, 1914.

Application filed June 7, 1913. Serial No. 772,246.

To all whom it may concern:

Be it known that I, FRANK J. BECKER, a citizen of the United States, residing at Hamilton, in the county of Butler and State 5 of Ohio, have invented certain new and useful Improvements in Molding-Flasks, of which the following is a specification.

My invention relates to a molding flask.

One of the objects of the invention is to 10 provide means forming a component of the flask for correctly drawing patterns.

Another object of the invention is to provide a flask having self-contained pattern-drawing mechanism, whereby molds can be 15 quickly, accurately and invariably formed by ordinary laborers, the principle of the invention being such that neither the services of an expert hand-molder, nor the experience of a skilled machine-molder, are required, the resultant products being superior 20 to either machine or hand-made molds.

Another object of the invention is to produce a molder's flask having pattern drawing mechanism on its sides, wherein the 25 parting plane is predeterminedly defined solely with respect to the flask structure, the flask members being separated invariably and precisely on this initially established parting plane and in the true direction of 30 the draft, that is, normally by motion directly at right lines to the parting plane, so that after the pattern is correctly molded in the sand, it may be so released that the molding surfaces defining both the pattern cavities and the parting plane, will be rendered 35 intact when disassociated from the forming elements.

Another object of my invention is to provide a flask with pattern drawing means enabling a given flask to be used for either 40 bench or floor work.

Another object of the invention is to so 45 mount or organize the pattern drawing means on the sides of the flask, preferably the pattern carrier, that it will operate in relation to conventional top and bottom mold frames, having hinge and latch provisions or its equivalent for opening up mold frames to release the mold cake.

50 Another object of the invention is to provide means for correctly separating the meeting surfaces of the mold sections, as well as freeing the surfaces defining the pattern cavities from the pattern.

The pattern drawing conditions are different and simpler where a conventional pattern or parting plate is employed, for there the mold sections are entirely separated from one another by the intermediate plate, and there is a clean separation between contacting metal and sand surfaces, but where the pattern spans a hollow frame there is a contact of sand on sand surrounding the pattern, and the common parting plane of the contacting sand particles must coincide with the original forming joint plane. 55 60 65

A flask embodying the principles of my invention is particularly desirable for job foundry uses, the flask itself constituting a 70 complete pattern-drawing mechanism, so that for "hurry orders" no machine equipment need be first prepared, the organized flask being adapted intrinsically for all exigency requirement. 75

I have shown the preferred embodiment of the invention in the accompanying drawings, forming a part of this specification, in view of which disclosure the underlying principle of the invention will be understood 80 by those skilled in the art, irrespective of the concrete structure and arrangement selected for illustrative purposes, wherein:—

Figure 1 is a side elevation of my invention, showing the flask sections and pattern 85 frame in a normal position for filling the cope and drag sections of the flask with sand. Fig. 2 is a view similar to Fig. 1 showing the parts in their separated position, after the mold has been finished. Fig. 90 3 is an end elevation in normal position of the parts. Fig. 4 is a top plan view of the pattern section illustrating also the mold section beneath. Fig. 5 is a section through one end of the pattern carrier showing the 95 rock shaft. Fig. 6 is a sectional view showing how the first or bottom mold section is conventionally formed. Fig. 7 is a section through the three flask members showing the mold completed and the flask members 100 separated.

I will first describe the flask components and operations for impressing the pattern in the mold, in order that the pattern-drawing requirements, and the principle of my 105 invention may be clearly understood.

The flask comprises the hollow, mating mold frames 1, 3, and the pattern carrier 2,

which are assembled one upon the other in the order of the reference numerals, the pattern bridging the hollow frame of carrier 2, so that it is ultimately solidly embedded in the sand of the three part shell constituting the flask. I refer to these members as "mating" because the sand cakes or mold sections to be separately formed in frames 1 and 3 are formed with mating or contacting faces constituting the parting plane, and with registering pattern cavities constituting the mold. Therefore, when the flask members are assembled with the pattern embedded in the sand, the forming elements must be so released that the cakes in separating from one another and freeing themselves from the pattern, will part on exactly the plane constituting the joint of the cakes as formed, so that when the finished cakes are joined to form the mold, they will correspond exactly to the position and condition of the sand as the pattern was originally embedded therein.

Fig. 6 shows the conventional first step in which 5 is a base, that portion of the pattern 4 of the carrier 2 of which an impression is to be made in the mold material of the upper frame 3 being embedded in the filling material of the base 5.

The material is first compacted into mold frame 1 and pattern carrier 2, when positioned on base 5, as shown in Fig. 6. The pattern carrier and frame 1 are lifted from the base, inverted, and frame 3 is placed on the pattern carrier. The material is then compacted into frame 3, around the pattern. The plane of contacting sand surfaces constitutes the parting plane for the pattern drawing. The pattern is thus solidly embedded in the sand of the assembled flask, except for the sprue formed through one of the cakes for pouring the metal.

My invention is more particularly directed to that type of the pattern carrier comprising a hollow frame spanned by the pattern where sand surfaces contact, defining a forming joint in the first instance and a parting plane in the operation of drawing the pattern.

I have detailed this conventional method of embedding the pattern into the two mold sections compressed together, because the means I have invented for drawing the pattern, operate with reference to the forming principle so far described. The sand cakes, or mold sections thus separately formed about the pattern, are to be so separated from one another and from the pattern as to preserve intact the surfaces defining the sectional pattern cavities as well as the contacting surfaces of the sand cakes defining the joint for both forming and parting the mold sections. These critical surfaces must not be disturbed in the act of separation or the mold will be injured or destroyed. The two cakes must part at the joint, and the

pattern must free itself from the sectional mold cavities. This is particularly difficult in drawing the pattern from the upper cake, the mold particles adhering by compression and being unsupported at the bottom, and it is also difficult to invariably part the cakes at the forming joint, so as to cleanly and perfectly preserve the meeting surfaces of the mold sections to be registered after their release from the forming elements.

The problem of correctly drawing the pattern has been a serious one in foundry practice, the skill of the most expert hand molders being independable and variable at best, so that many attempts have been made to produce the desired results by attaching devices to the flask members, as well as by attempts to incorporate the said members as elements of an organized and expensive machine.

The parting joint extends cross sectionally relative to the pattern carrier 2, and the set surfaces so carefully formed and so perishable must be preserved to make a perfect mold. To effect this result, I provide actuating means attached directly to one of the three flask members and coacting in relation to all three members when the pattern is being released from the sectional pattern cavities, and the joint surfaces of the cakes are being separated from one another. The principle of my three part separating coaction is such that the strains become critically effective at the theoretical parting plane and exerted in true right lines relative to this plane.

It is a principle of my invention that the strains of the separating mechanism are uniformly exerted in the direction transverse to the parting plane, the movements of the flask members responsive to the strains being preferably mechanically guided in true right lines relative to the parting plane, wherefore, the mold sections will of necessity separate at the forming joint and the pattern will relatively move from the sectional mold cavities in the true line of draft. In other words, the separating influences will be a reproduction of the pattern cavity forming influences exerted in exactly an opposite direction. Preferably, I provide four jack members 6 specifically in the nature of cams, which function as separating instrumentalities for pattern drawing. Said members 6 are fulcrumed on the outer sides of the pattern carrier 2, one at each of the four ends of the rectangular frame, two on a side, the rock shafts 11 are preferably fixed to the middle portions of the jack 6, the extending ends having anti-friction rollers 7, 8, respectively contacting the top and bottom rim surfaces 9, 10, of members 3 and 1, between which the elements 6 are positioned, these rims ex-

tending flange-like from the vertical walls of said flask frames. Preferably rock shafts 11 constitute the fulcrums rotatable on the pattern carrier 2, the members 6 being fixed 3 to turn therewith. From each rock shaft is projected a rock arm 12. On one side of frame 2, at the medial line thereof, I place a fulcrum post 13, to which is pivoted a lever 14, the inner end 15 of which projects beyond the fulcrum point. For connecting the rock arms 12 with the actuating lever arm 14, I provide two links 16, pivotally connected at their inner ends to said lever arm upon opposite sides of its fulcrum, the 10 outer ends of said links being pivotally connected to the rock arms 12, at the corners of the frame. When the flask members 1, 2, 3, are assembled for forming the upper mold section, as shown in Fig. 1, the lever 14 is 15 in its lower position, the elements 6 extending in substantially horizontal plane, the three rim surfaces of the flask members mutually contacting. When lever 14 is slowly raised, the members 6 will start turning to 20 their vertical position, shown in Fig. 2, separating the members 1, 2, 3, from one another, parting the meeting surfaces of the mold sections at the forming joint, and simultaneously releasing the pattern from the 25 upper and lower sectional mold cavity surfaces.

The movements of the flask members are directed by guides 16, 17, in true right lines taken from the parting plane, regardless whether or not the flask sets level.

The separating impulse is exerted at the parting plane, the relative movements starting at the same time, but a full throw of lever 14 will bring the members 1, 2, 3, a predetermined distance apart, sufficient not only to part the mold joint but to completely release the pattern from the upper and lower sectional pattern molds, the finished cakes can then be taken out of the frames 45 1 and 3, by unlatching the fastenings 18, and the mold sections united.

The parallelism of the rim surfaces 9, 10, with the forming joint or parting plane, and the right angle guide members 16, 17, 50 cause the leverage stresses to be exerted in the line of draft, regardless of the position of the flask, and the members to relatively move in this theoretical line of draft, the leverage of the separating mechanism 55 being controlled solely by the structural correlation of the three flask members with which it has mutual coaction.

With a flask of this character, a green hand can make molds quicker and better 60 than a skilled hand-moldér.

The pattern drawing is also more correct than in that class of molding machines wherein the flask members are incorporated as working elements, and particularly where 65 the lifting is done from the table and floor

which is not necessarily parallel with the parting plane. It is the accomplishment of this result by means entirely supported by and operating equilaterally upon the sides of the flask, to impart to each of the three flask members said relative movements, from a position of relative contact, which constitutes the essential principles of my invention.

The plane wherein the sand particles of the upper mold contact the sand particles of the lower mold, constitute the forming joint of sand on sand in the first instance and the desired parting plane in the second operation, and these surfaces must be separated; while the sand particles forming the surface of the mold cavities contacting the pattern, constitute contacting surfaces, of sand on metal, and these different characters of contact surfaces must be also correctly separated in the pattern drawing operation.

In view of this disclosure it is evident that the principles of my invention are susceptible of embodiment in a variety of forms differing specifically from what is shown in the drawings.

Preferably I provide steps 20, 21, on the sides of the flask definitely positioning the three-part flask members relative to one another for the forming operation.

The specific preferred arrangement of separating mechanism is shown in Figs. 2 and 4, from which it will be seen that the lifting lever, or actuator 14, is placed on the front side of the flask, the rock shafts 11 spanning the pattern carrier outside of the frame, the cams 6, on the rear of the frame being fixed thereto, so that a single actuating lever on the front of the flask may be employed. The cams 6, are connected in pairs at each end of the frame, effective at the four corners, whereby the lifting agency is energized by compound leverages.

It will be understood by those skilled in the art that 28 is the hinge of mold frame 1 for opening up the frame to release the finished mold section, and that frame 3 has a similar hinge diagonally disposed as to latch 18, while the mold frame 1 has a similar latch 18 diagonally disposed in reference to the corner hinge 28.

It is highly advantageous to provide a pattern drawing mechanism directly mounted on the sides of the flask which can be used in connection with this type of opening up mold frames, and not requiring some special structural mold frame not readily adaptable for general foundry work.

The cams or levers 6 are lifting jacks co-acting with flask abutments to relatively separate the three flask members. They are disposed around the sides of the flask so as to exert uniform separating strains in right lines to the parting plane. They not only ef-

fect the separation but form a support for the flask members in their separated positions, the actuating lever mechanism preferably passing a dead center to additionally insure a support at the end of the separating movements, as is plainly shown in Fig. 2. Preferably each of the jacks is double acting to exert upward and downward strains against abutments so that the member carrying the jacks and the members carrying the abutments relatively move apart from one another and into a supported position of three-part separation.

The mold frames with the hinged sides or other separable provision for releasing the mold cakes are conventionally known to the trade as snap flasks, or snap mold frames.

The lever mechanism in moving to final position causes a dead center so as to support the superposed parts as shown in Fig. 2. The upper frame can then be removed, the pattern carrier taken off of the lower mold frame and placed on the member 5, as shown in Fig. 6, ready for forming the next mold section, the upper and lower mold frames are brought together, and the two mold frames are then unlatched, and so the mold is formed. The lower frame 1, is placed on the frame 2, as shown in Fig. 6, and the operator is ready to start on a new mold.

The frame member itself carries the separating mechanism constitutes an article of manufacture for use in connection with half flasks, that is to say, the upper and lower mold frames commonly known as the cope and drag which together form a flask. Said member is adapted to be detachably supported by the flask in such position that the separating mechanism can coöperate with said flask members for separating them on the parting plane. A preferred embodiment of the invention is thus in the nature of a molder's appliance for use in connection with two-part flasks, the particular method of handling the pattern being left somewhat to the discretion of the foundryman.

Having described my invention, I claim:—

1. A pattern drawing device comprising mold frames and an intermediate pattern carrier, constituting separable flask members, and separating means supported on the pattern carrier and coacting with all three members to relatively separate them each from the other in right lines to the parting plane.

2. A molder's flask comprising snap mold frames, and an intermediate pattern carrier, said snap frames having rim surfaces constituting abutments in parallelism with one another and with the plane of the forming joint of the mold sections, means guiding said members in right lines relative to said surfaces, and lever mechanism supported on one of said members and operating between

said abutment surfaces, whereby all three members may be relatively moved to separate the mold sections on the predetermined parting plane, and to release the pattern from the mold cavity surfaces.

3. A molder's flask comprising snap mold frames and an intermediate pattern carrier, lever mechanism supported by and coacting with the flask members for simultaneously and uniformly effecting a relative movement of said three members each from the other, and an actuator on one side of the flask for operating said separating mechanism upon opposite sides of the flask.

4. A device adapted to form one of the assembled elements of a molder's flask, lifting jacks and operating mechanism supported on the sides of said device, the lifting jacks being adapted to coöperate in relation to hinged mold frames, constituting separable members of the flask.

5. A three-part separable molder's flask, having abutments, coacting jacks fulcrumed on the sides of the flask, and a jack actuating means fulcrumed on the sides of the flask for operating said jacks in unison, said jacks and actuating means comprising a pattern drawing mechanism self-contained on the flask, the abutments and jacks being relatively disposed to effect a simultaneous three-part flask separation.

6. A molder's flask comprising snap mold frames and an intermediate pattern carrier constituting a three-part separable flask, a unitary lever mechanism supported by said flask members and operating simultaneously and uniformly on opposite sides thereof in correlation to all the members to relatively separate them from the parting plane of the mold sections, and means on one side of the flask for operating said separating mechanism upon opposite sides of the flask.

7. A pattern carrier for a molder's flask having lifting jacks disposed around the sides and means on the pattern carrier for simultaneously actuating said jacks.

8. A device of the nature disclosed comprising mold frames and an intermediate pattern carrier constituting a three-part separable flask, pattern drawing means supported on the sides of the pattern carrier adapted to coact with the mold frames to relatively separate the three flask members, means guiding the direction of movement of said members, and an actuating element for simultaneously operating said pattern drawing means.

9. In combination with mold frames and an intermediate pattern carrier, constituting a three-part separable flask, pattern drawing means supported on opposite sides of said pattern carrier and operating with respect to the mold frames, to relatively move the three flask members from contacting po-

- sition to pattern releasing position, means guiding said movement in right lines to the parting plane, and means for simultaneously operating said pattern drawing means.
- 5 10. A molder's flask comprising mold frames and a pattern carrier, cams on opposite sides of the pattern carrier, having one position in which the flask members respectively contact, and a. other position in which 70 said three flask frames are relatively separated, guides for said movements, and means for simultaneously actuating said cams.
- 10 11. A molder's flask comprising mold frames and a pattern carrier, cams on opposite sides of the pattern carrier coacting with bearing surfaces on the two mold frames, 75 said cams being adapted to be turned to relatively separate the flask members and pattern carrier, means guiding said flask members in right lines to the predetermined 80 parting plane of the mold sections, and means for simultaneously actuating said cams to separate said members from the parting mold plane and for releasing the 85 pattern from the mold sections.
- 20 12. In a molder's flask, mold frames having marginal flanges, and means for intermediately supporting a pattern, cams on opposite sides of said means between said marginal flanges, and means for simultaneously 90 actuating said cams to exert opposing strains on said marginal flanges for relatively separating the flask members.
- 30 13. A molder's flask comprising pattern supporting means and two snap mold frames, and mold frame separating mechanism mounted on the sides of the flask for drawing the pattern, said mechanism being so located as to permit the opening of both 95 the upper and lower mold frames.
- 40 14. A molder's flask comprising snap mold frames and an intermediate pattern carrier, constituting a three-part separable flask, devices secured on the sides of the 100 pattern carrier for imparting simultaneous relative separating movements to each of said three flask members, and an actuator secured on the sides of the flask for operating said separating devices.
- 45 15. A molder's flask comprising an upper and lower mold frame, and means supporting a pattern, mechanism mounted on the sides of the flask and operative between said mold frames for relatively separating them 105 and drawing the pattern, said mechanism being so located as to permit both mold frames to be opened up after the pattern drawing operation.
- 50 16. In combination with mold frames, an intermediate pattern carrier, separating devices secured on the sides of the pattern carrier, and a lever fulcrumed on the sides of 110 said pattern carrier coacting with said separating devices for actuating them.
- 55 17. A molder's flask comprising mold frames, and means intermediately supporting a pattern, lever mechanism on the sides of the flask movable to relatively separate the mold frames and pattern supporting means, said lever mechanism crossing a dead center at the end of its separating movement and forming a fixed support for the upper mold frame members.
- 60 18. A molder's flask comprising snap mold frames and an intermediate pattern carrier, 115 constituting a three-part separable flask, separating devices fulcrumed on the sides of the flask, and an actuating device fulcrumed on the sides of the flask for operating said separating devices thereby relatively separating said flask members each from the other.
- 65 19. A molder's flask comprising hollow frames and means supporting a pattern, shafts extending across opposite walls of the flask, separating devices on the opposite 120 ends of said shafts, and means connecting said shafts for operating them in unison.
- 70 20. A molder's flask comprising mold frames and pattern carrier, mechanism on the carrier for relatively separating the mold frames and drawing the pattern, said mechanism forming a fixed support for the superposed members at the end of the pattern drawing movement.
- 75 21. A pattern drawing device comprising mold frames and an intermediate pattern carrier constituting a three-part separable flask, rock shafts spanning the opposite 125 ends of the pattern carrier outside of the molding material receiving space, cams fixed to the ends of said rock shafts coacting to relatively separate said flask members each from the other, and lever mechanism on one side of the flask for simultaneously actuating said rock shafts.
- 80 22. A molder's flask comprising mold frames, an intermediate pattern carrier, and means supported on the sides of the pattern carrier, coacting with the three-part separable members to move them to mold separating and pattern releasing position, said means comprising elements exerting uniform separating strains at predetermined 130 points relative to the sides of the flask, and an actuator on the side of the pattern carrier having motion transmission connection with said separating means.
- 85 23. A three-part separable molder's flask having abutments, coacting jacks and jack actuating means, said jacks and actuating means comprising a pattern drawing mechanism self-contained on the flask, the abutments and jacks being relatively disposed to effect a three-part flask separation and 135 support.
- 90 24. A three-part separable molder's flask having abutments, coacting jacks and lever mechanism actuating the jacks, said jacks and actuating means comprising a pattern 140

drawing mechanism self-contained on the flask, the abutments and jacks being relatively disposed to effect a three-part flask separation and support, the lever mechanism passing a dead center when the jacks support the separated flask members.

25. A three-part separable molder's flask having abutments, double acting jacks therefor exerting opposing strains between the 10 abutments, and jack actuating means, said jacks and actuating means comprising a pattern drawing mechanism self-contained on the flask, the abutments and jacks being relatively disposed to effect a three-part 15 flask separation.

26. A three-part separable molder's flask having abutments, fulcrumed lifting jacks and fulcrumed actuator, and connections between the jacks and actuator forming a pattern 20 drawing means self-contained on the flask, the jacks and abutments relatively disposed to exert uniform strains around the sides of the flask and simultaneously effecting a three-part separation of the flask 25 members.

27. A molder's flask comprising pattern supporting means, and two mold frames, the members of each of which are formed to open and close for releasing the finished 30 mold from the said frames, and pattern drawing mechanism on the sides of the assembled flask for effecting a mold frame separation, permitting said frames to be opened up after the pattern is drawn.

35. 28. In combination with top and bottom mold frame members, an intermediate member, said members constituting an assembled molder's flask, said intermediate member having devices operating in relation to all 40 three members to separate each from the other.

29. A member adapted to be assembled into a molder's flask comprising snap mold frames, having means cooperating with the

5 snap frames to relatively separate them for 45 drawing the pattern.

30. A bottom mold frame and a pattern carrier seating thereon, means on the pattern carrier for lifting it from the bottom frame, and an actuator on the pattern carrier 50 for operating said lifting means in unison.

31. A molder's flask comprising snap mold frames, means supported on the sides of the flask coöperating with the snap 55 frames for relatively separating them, and an actuator supported on the sides of the flask for operating said means in unison.

32. A molder's flask comprising snap mold frames formed with parallel rim surfaces constituting abutments, means supported on the sides of said flask coöperating with said abutments to separate said mold frames from one another, and an actuator on the sides of the flask for operating 65 said means in unison.

33. A molder's flask comprising mold frames and pattern supporting means, each of said frames having its members formed to open up a frame for releasing the mold 70 section therefrom, mechanism supported on and operating uniformly around the sides of the flask for relatively separating the frames and relatively separating them from the mold sections.

34. A molder's appliance for use in connection with a two-part flask, and comprising a member adapted to be detachably supported thereby, and mechanism carried by said member and adapted to cooperate with 80 and separate said flask parts.

In testimony whereof, I have hereunto set my hand.

FRANK J. BECKER.
